ABSTRACT

A vibration-responsive apparatus having means for detecting a vibration and producing a signal in response to the detected vibration, and electric circuit means operating in response to the vibration when it lasts for more than a certain period of time and the signal corresponding thereto is produced a predetermined number of times, the electric circuit means being adapted to actuate a desired device connected thereto.

VIBRATION-RESPONSIVE APPARATUS

This is a continuation, of application Ser. No. 887,211, filed Dec. 22, 1969 now abandoned.

BACKGROUND OF THE INVENTION**1. Field of the Invention**

This invention relates to a vibration-responsive apparatus for use with an object to be protected such, for example, as a safe, and more particularly to a vibration-responsive apparatus which, for example, gives an alarm upon detection of vibrations through air, a solid or the like which are caused by an intruder who is going near the safe or the like.

2. Description of the Prior Art

Almost all the conventional alarm devices of this type raise an alarm in response to only one vibration. Consequently, these prior art devices the disadvantage that vibrations caused by a person other than an intruder, for example, noises and accidental touch on the safe or the like to be guarded lead to a false alarm.

SUMMARY OF THE INVENTION

Accordingly, a primary object of this invention is to provide a vibration-responsive apparatus which is capable of giving an alarm in response to a vibration which is produced intermittently for more than a predetermined period of time or produced intermittently a predetermined number of times.

Another object of this invention is to provide a vibration-responsive apparatus which is simple in construction and inexpensive but capable of responding to only specific vibrations to raise an alarm.

Other objects, features and advantages of this invention will become apparent from the following description taken in conjunction with the accompanying drawings.

BRIEF DESCRIPTION OF THE DRAWINGS

FIG. 1 shows in block form a vibration-responsive apparatus of this invention; and

FIG. 2 is a circuit connection diagram showing one example of the vibration-responsive apparatus depicted in FIG. 1.

DESCRIPTION OF THE PREFERRED EMBODIMENTS

With reference to the drawings one example of this invention will hereinafter be described in detail. Reference character A designates a vibration detector or vibration-sensitive element, which is a pressure-sensitive element such as a so-called piezoelectric element formed of Rochelle salt, ceramic or the like. In this case, it is preferred to use a pressure-sensitive element which has a frequency characteristic such that it detects only vibrations or sound waves of relatively high frequencies but does not pick up gentle vibration of the safe itself due to, for example, earthquake shock or the like. The pressure-sensitive element may be substituted with, for example, an electromagnetic, moving-coil type or like microphone, which is desired to have a characteristic such that it picks up sounds (vibrations) of relatively high frequencies but does not respond to vibrations of very low frequencies. In the event of using a pressure-sensitive element designed for detecting vibrations of a wide frequency range, suitable means such as a high-pass filter which cuts off a low-frequency range of, for example, less than 30 Hz is pro-

vided on the output side of the pressure-sensitive element. The pressure-sensitive element A is mounted on the door of the safe or on the inside thereof or disposed in a room where the safe is placed. The electric output

5 of the detector A corresponding to a vibration picked up thereby is amplified by an amplifier B and is then applied to a delay switching circuit C. The delay switching circuit C produces a signal of a constant duration irrespective of the duration of the signal fed thereto. 10 Namely, even when supplied with a signal of a short duration of less than 4 seconds produced corresponding to a vibration detected by the detector A, the circuit C produces a signal of a constant duration of, for example, about 4 seconds and, further, when supplied with 15 a signal of a relatively long duration, the circuit C produces a desired number of signals, each having the predetermined duration (about 4 seconds).

The delay switching circuit C drives a trigger circuit

20 D which is preferred to be actuated by a relay and its contacts operated by the delay switching circuit C. The trigger circuit D is a circuit which supplies in pulse form an output signal corresponding to the number of vibrations picked up by the detector A or a signal representative of the duration of the number of vibrations.

25 On the output side of the trigger circuit D there is disposed a ring counter E for reading out the number of the vibrations. The output of the trigger circuit D is counted by the ring counter E. Namely, when the detector A picks up a predetermined number of vibrations

30 the ring counter E counts the number and when the detector A picks up a signal of a relatively long duration the vibration is converted by the delay switching circuit C into signals of a predetermined duration and the number of the resulting signals is counted by the ring counter E and a main alarm oscillator circuit F is selectively activated in accordance with the number of the outputs of the ring counter E. Thus, an alarm signal is transmitted to a predetermined location to operate an alarm device G, for example, a bell or the like which

40 is located, for instance, in a guardman's room remote from the safe or the like to be protected. It is preferred to provide a circuit I which raises a warning signal at every detection of such a vibration as previously mentioned.

45 In the case where the setting operation of this apparatus is likely to produce a vibration to cause accidental actuation of the device, it is desirable to set the apparatus to initiate its operation a certain period of time after the setting of the apparatus. To this end, it is preferred to employ a delay switching circuit H in association with the trigger circuit D.

50 A description will be made in connection with one example of the circuit construction embodying this invention.

55 Referring to FIG. 2, a description will be given first of one example of the delay switching circuit C. Namely, the output of the amplifier B is rectified by a diode D' and its rectified output is applied to a transistor Q₁. A transistor Q₂ is connected to the transistor Q₁, the collector of which is connected through a capacitor C₂ to the base of the transistor Q₂ which is connected to the negative electrode of a power source J₁ through a resistor R₁ and a switch S_b described later. The transistors Q₁ and Q₂ are designed to constitute a kind of a bistable multivibrator and the capacitor C₂ and the resistor R₁ form a time constant circuit of the bistable multivibrator. Namely, the transistors Q₁ and Q₂ are interconnected in a manner to be alternately switched on

and off to produce rectangular waves m at regular time intervals as shown at the top of the figure. Connected to the output side of the transistor Q_1 is a relay Y_a , whose contacts a_1 and a_2 are adapted to be opened and closed under the control of the transistor Q_1 . The relay Y_a and its contacts a_1 and a_2 correspond to the trigger circuit D previously described with FIG. 1.

The operation of the delay switching circuit C will be described. When a signal derived from the amplifier B is rectified by the diode D' to make the right-hand side of the capacitor C_1 negative relative to its left-hand side, the transistor Q_1 is switched on and the transistor Q_2 is switched off. This switching is determined by a time constant circuit consisting of the capacitor C_2 and the resistor R_1 and the rectangular wave current indicated by m is applied to the relay Y_a to achieve make-and-break of its contacts a_1 and a_2 in accordance with the curve m .

In the event that a signal of a short duration is fed to the delay switching circuit C to switch the transistor Q_1 , the relay Y_a conducts at least for a period of time corresponding to the duration of a first one of the rectangular wave signals m to close the contacts a_1 and a_2 , thereby to constitute a closed circuit of a power source J_2 —a buzzer Z_1 —the contact a_1 —the power source J_2 , causing the buzzer Z_1 to raise an alarm. Namely, even in the case of a signal whose duration is shorter than that of one rectangular wave m , the buzzer Z_1 is made to ring for a period of time corresponding to the duration of one rectangular wave m .

When the delay switching circuit C is supplied with a signal of a sufficiently long duration, the transistors Q_1 and Q_2 serve as a bistable multivibrator for a period of time corresponding to the duration of the signal, that is, they are alternately switched on and off to produce an output such as indicated by the curve m to activate the relay Y_a intermittently in accordance with the curve m , causing its contacts a_1 and a_2 to make and break correspondingly.

The ring counter E used in this invention may be a usual one. In the present example, however, the ring counter E is made up of four active elements such as thyristors SC_1 to SC_4 and at every arrival of a pulse the ring counter E repeats conduction and nonconduction as usual. In this case a thyristor SC_0 is connected to the stage preceding the thyristor SC_1 of the ring counter so as to ensure that the first thyristor SC_1 is caused to initiate its operation by a first signal and that the following thyristors are sequentially controlled to be conductive and non-conductive. To this end, there are provided a capacitor C_4 and a resistor R_2 , the capacitor C_4 being charged by the power source J_1 when a power source switch S_b for closing the circuit of the power source J_1 is closed and the resistor R_2 passing therethrough the charging current. When the capacitor C_4 is charged in accordance with the time constant determined by the capacitor C_4 and the resistor R_2 , a pulse n depicted in the figure is applied to the control electrode of the thyristor SC_0 to switch it on first.

Namely, when the relay contact a_2 is closed only one differentiated pulse is generated through the capacitor C_4 and the resistor R_2 to trigger only the thyristor SC_0 , thus ensuring that counting starts from the thyristor SC_0 . Any one of the thyristors other than SC_0 , for example, SC_1 cannot be triggered by a signal which is integrated by a resistor R_{13} and a capacitor C_6 , attenuated by resistors R_{10} and R_{11} and leaking from a differenti-

ation circuit consisting of a capacitor C_4' and a resistor R_{12} . Under such conditions, the capacitor C_5 is not charged but the capacitor C_6 remains charged and the cathode of a diode D_2 is in a reverse biased condition.

- 5 Consequently, when an input trigger voltage is lower than the value of the reverse bias, the diode D_2 can conduct but the thyristor SC_0 is conductive to cause the voltage drop across the resistor R_{11} to be zero, so that the input pulse is fed through the diode D_1 and the capacitor C_4' to the thyristor SC_1 to cause it to conduct. At the instance that the thyristor SC_1 becomes conductive, a differentiated pulse is generated across the resistor R_4 connected in common to the cathodes of the thyristors to instantaneously make the cathode of the thyristor SC_0 positive and the thyristor SC_0 by having its anode held at zero potential is reversely biased and turned off. The thyristor next to SC_1 is also turned off. In this manner, the counting advances one step in response to one input pulse. Subsequently, the thyristors sequentially conduct at every arrival of an input pulse and when the thyristor SC_4 has become conductive a relay Y_b' is energized to close its contact b and hence provide a closed circuit of a power source J_3 to the buzzer Z_2 through the contact b to ring the buzzer Z_2 .

- 25 The operation of the present device may be summarized as follows.

When a vibration of a relatively high frequency is picked up by the detector A , an electric signal corresponding to the vibration is supplied to the switching

- 30 circuit C to cause it to actuate the relay Y_a as above described. In this case, however short the vibration may be, an output signal corresponding to it is derived from the delay switching circuit C for the time corresponding to one rectangular wave m to actuate the relay Y_a , causing the buzzer Z_1 to raise a preliminary alarm and turning off the thyristor SC_0 and on that SC_1 . Similarly, the present apparatus operates at every occurrence of vibration and when the vibration has occurred four times the main alarm oscillator circuit G operates to

- 40 sound the buzzer Z_2 .

In the event that a signal of a long duration is applied to the delay switching circuit C , an intermittent signal of a rectangular wave m is derived from the circuit C to ring the buzzer Z_1 and turn on and off the contact a_2 at every occurrence of the intermittent signal and when the intermittent signal produces four or more pulses or when the signal continues for a period of time of more than four pulses the buzzer Z_2 is similarly caused to ring to give an alarm for an intruder. Even when the signal does not continue for such a period of time, if it continues for a time long enough to actuate any one of the thyristors SC_1 to SC_4 , the main buzzer Z_2 is not actuated immediately but it is operated later when the signal is produced so many times or for so long a time as to operate the thyristor SC_4 .

In short, once the four stages of the thyristors SC_1 to SC_4 have been turned on and off in a sequential order, the buzzer Z_2 is rung to raise an alarm irrespective of whether the incoming signal is a series of short-duration signals or a continuous signal. Otherwise, the buzzer Z_1 is energized to give a preliminary alarm at every changing over of each thyristor.

65 In order to avoid accidental operation of this invention apparatus which might be caused by vibrations during the setting operation of the apparatus, an operator's walking or other accidental vibrations, it is preferred to employ a delay switching circuit H .

Referring to FIG. 2, one example of the delay switching circuit H will hereinbelow be described. Reference characters S₁ indicates a manual switch having connected in series thereto a relay Y_b which is connected to the minus side of the power source J₁. The relay Y_b serves to operate the power source switch S_b. The delay switching circuit H includes a kind of bistable multivibrator with transistors Q₃ and Q₄ and in this case the circuit H is adapted not to actuate the relay Y_b immediately when the switch S₁ is turned on. The time constant of the bistable multivibrator is determined by a capacitor C₇ and a resistor R₈ which are interposed between the transistors Q₃ and Q₄. Reference characters R₅ and R₆ designate bias resistors for the base of the transistor Q₃, R₇ a resistor incorporated in the circuit for charging the capacitor C₇ and R₉ a resistor interposed between the emitters of the transistors Q₃ and Q₄ and the plus side of the power source J₁. The operation of the above circuit will hereinbelow be outlined. In the steady state of the circuit H, the transistor Q₃ is in the off state and the base current of the transistor Q₄ flows but when the manual switch S₁ remains open the collector current of the transistor Q₄ does not flow. The capacitor C₇, which is coupled with the resistor R₈ to determine the delay time, is always charged through the base and emitter of the transistor Q₄. Further, the emitter voltage of the transistor Q₃ is held a little negative by the resistor R₉ so as to ensure that the transistor Q₃ is turned off. Closing the manual switch S₁, a negative voltage is applied to the base of the transistor Q₃ to turn it on. When the transistor Q₃ is turned on, its collector current flows to cause a voltage drop across the resistor R₇ and this voltage change is applied through the capacitor C₇ to the base of the transistor Q₄ to hold it at a positive potential, so that the transistor Q₄ is turned off and no current is fed to the relay Y_b. While, the base of the transistor Q₃ is supplied with a higher negative voltage and this voltage is maintained at the moment of reversal of the operation of the bistable multivibrator. The capacitor C₇ is discharged through the collector and emitter of the transistor Q₃ to make the base of the transistor Q₄ negative. Immediately when the base of the transistor Q₄ is rendered negative, the operation of the circuit is reversed and the relay Y_b operates to return the collector potential of the transistor Q₄ to its saturated potential, thereby turning off the transistor Q₃. With this delay switching circuit H, the apparatus of this invention initiate its operation about 15 seconds after setting.

Consequently, the relay Y_b does not operate immediately after the closing of the switch S₁ but initiates operation after a certain period of time, for example, approximately 15 seconds to turn on the power source switch S_b. This leads to the normal operation of this invention apparatus described above, so that if the operator leaves the apparatus within about 15 seconds after setting, no accidental actuation of the apparatus occurs due to vibrations caused by him.

As has been described in the foregoing, the apparatus of this invention is designed to pick up mechanical vibrations or sound waves caused when an intruder approaches or touches the safe or enters a room where the safe is placed and to raise an alarm when the number and the duration of the vibrations have reached certain values, thus ensuring the protection of the safe from theft.

Although the present invention has been described in connection with the case where an alarm is given when the number and the duration of mechanical vibrations caused by an intruder have reached a certain value, the invention is not limited specifically to the above but the vibration-responsive apparatus of this invention may be designed to achieve a desired operation or control other device when vibrations caused at unspecific times continue by a certain number of times or for a certain period of time. Accordingly, the present invention provides a control device adapted not to respond to a vibration caused less than a certain number of times, for example, four times or for a shorter period of time than a predetermined one but to achieve various operations such as previously described when vibrations are caused a predetermined number of times. Further, since the apparatus of this invention is designed to initiate operation after a long period of time within which an operator can leave from the place where the apparatus is located, care need not be taken to prevent vibrations during setting of the apparatus.

Although the present invention has been described as applied to the alarm device which gives an alarm in response to vibrations caused four times or a signal continuing for a time corresponding thereto, it is needless to say that this number may be altered as desired.

It will be apparent that many modifications and variations may be effected without departing from the scope of the novel concepts of this invention.

I claim as my invention:

1. A vibration responsive apparatus for detecting mechanical vibrations propagated through a solid or fluid comprising:

means for detecting said mechanical vibrations and producing an electrical output signal when said mechanical vibrations occur;

a first electrical wave generator receiving the electrical output signal from said detecting means and producing a pulse of standard time length each time an electrical output signal is received from said detecting means and producing a series of standard time length pulses if said electrical output signal from said detecting means persists longer than said standard time length, said first electrical wave generator comprising a multivibrator including a pair of transistors with a period equal to said standard time length;

a pulse generator connected to the output of said first electrical wave generator and producing a pulse each time a standard time length pulse is generated by said first electrical wave generator;

a second electrical wave generator receiving the output of said pulse generator and comprising a ring counter for counting said pulses; and

an output warning device connected to the output of said second electrical wave generator and producing an alarm if a predetermined number of standard time length pulses are produced by said first electrical wave generator.

2. A vibration responsive apparatus according to claim 1 wherein said pulse generator comprises a relay connected to the output of said first electrical wave generator and closed each time a pulse of standard length is received, a first silicon controlled rectifier with its output connected to said electrical wave generator, a voltage source, a capacitor connected between said voltage source and the gate electrode of said first

silicon controlled rectifier, and a switch connected across said capacitor and controlled by said relay.

3. A vibration responsive apparatus according to claim 2 including a resistor connected between the gate of said first silicon controlled rectifier and said second electrical wave generator.

4. A vibration responsive apparatus according to claim 2 wherein said ring counter includes a plurality of cascaded silicon controlled rectifiers connected to

form a ring counter with the gate of the first of said cascaded silicon controlled rectifiers connected to said first silicon controlled rectifier and the gates of succeeding cascaded silicon controlled rectifiers connected to the outputs of preceding silicon controlled rectifiers and the last of said cascaded silicon controlled rectifiers connected to said output warning device.
